UNITED STATES PATENT OFFICE.

GEORGE B. THOMAS, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

ELECTRIC FITTING.

1,329,330.

Specification of Letters Patent. Patented Jan. 27, 1920.

Application filed April 30, 1919. Serial No. 293,685.

To all whom it may concern:

Be it known that I, GEORGE B. THOMAS, a citizen of the United States of America, and residing at Bridgeport, in the county of 5 Fairfield and State of Connecticut, have invented a certain new and Improved Electric Fitting, of which the following is a specification.

My invention relates to electric fittings 10 and particularly to lighting fixtures, the object of my invention being to provide such means for securing together a lamp socket and a reflector or its holder that the position of a lamp in the socket may be properly located with relation to the focal center of the reflector.

In the accompanying drawings—

Figure 1 is a vertical section through a shade or reflector holder showing a lamp 20 socket mounted therein in accordance with my invention;

Figs. 2 and 3 are respectively plan views of the opposite ends of the socket;

Fig. 4 is a central section through the 25 socket mount;

Fig. 5 is a development of one feature of the socket;

Fig. 6 is a section through a shade holder and socket showing a modified construction;

30 Figs. 7 and 8 are plan views of the opposite ends of the socket; and

Fig. 9 is a development of one feature of the socket.

There is little uniformity in the size and 35 construction of the holders used in commercial lighting fixtures for supporting the associated reflectors or globes. Furthermore, there is a considerable variation in the focal points of different types of reflectors and globes. In order to secure the greatest 40 efficiency in the lighting fixture, however, it is necessary that the lamp be located with approximate exactness at the focal center of the reflector or globe. The present invention aims to provide simple means by which the 45 position of the socket may be adjusted to the dimensions of the shade or globe holder so that the lamp may be properly positioned with relation to the focal center of the reflector. While the invention may be applied to various types of lamp socket and shade 50 holders or reflectors, I have illustrated it in connection with a lamp socket and shade holders of the types commonly now used in 55 commercial lighting fixtures.

Referring first to the construction shown in Figs. 1 to 5 the socket has a one-piece porcelain body 10 with a central well to accommodate the screw shell 11 and center contact 12 of an Edison lamp receptacle, 60 into which the lamp 13 is screwed. Piercing the body 10 outside the well are holes 14 and 15 through which the wires are led to the binding screws 16 and 17 carried by the terminal plates 18 and 19. These plates are 65 electrically and mechanically connected by screw bolts 20 and 21 to straps 22 and 23 at the back of the socket, and these in turn are respectively connected to the screw shell and center contact by screw bolts 24 and 25. 70

In order to mount the socket within the shade holder 26 and to secure the parts together, I provide a carrier or yoke having legs 27 and 28 with offset feet 29 and 30, each tapped at 31 to receive a securing bolt 75 32 passing through the body of the socket. The yoke piece is shouldered at 33 and a screw nipple 34 provided which projects through a hole 35 in the top of the shade holder and its associated cap 36. The nut 80 37 secured on the nipple 34 serves to clamp the parts of the shade holder together and to the yoke.

The adjustment of the socket with relation to the shade holder is secured by recessing the back or inner end of the socket to form two like arcuate groups of steps 85 38, 39, 40 and 41 of any convenient depth, arranged on opposite sides of the axis of the socket. Each step is of sufficient size to 90 accommodate one of the feet 29 or 30 of the yoke. The body of the socket is pierced by corresponding groups of holes 42, 43, 44 and 45, each opening to one of the steps and serving to accommodate one of the 95 securing screw bolts 32. In order that the same screw bolt may be used irrespective of the particular pair of steps upon which the feet of the yoke are rested, the holes are shouldered at 46, at a uniform distance from 100 the face of the step, to form a seat for the head of the bolt.

It is obvious that by resting the feet of the yoke upon different pairs of steps the lamp socket is shifted longitudinally on the 105 axis of the shade holder, the extent of longitudinal adjustment being limited by the distance between the step 38 on the one hand, and the step 41 on the other hand. For any of the adjustments the same yoke and 110

the same bolt are utilized, and the only operation necessary to effect the adjustment is to remove the bolts from one pair of holes 42-45 and insert them in the pair leading 5 to the ledges against which the feet of the yoke are rested, the socket being rotated on its axis and longitudinally shifted to bring the desired pair of ledges into engagement with the feet of the yoke.

10 Turning to the modification shown in Figs. 6 to 9, the shade holder 47 here shown is of a different type and depth. The socket carrying yoke is also of a slightly different construction, comprising a straight bar 48 carrying the nipple 49 and nut 50, and having at its opposite ends posts 51 which are adapted to receive the screw bolts 32. The main features of the socket construction are the same as those previously indicated, the 20 sole difference being that instead of providing groups of external stepped ledges, as in Figs. 1 to 5, the latter are substituted by a series of independent wells 53, 54, 55 and 56 of different depths. With these communicate perforations 57, 58, 59 and 60, through which the securing bolt passes, and against the corresponding stepped shoulders 61 of which the heads of the bolts rest. Obviously the same facility of longitudinal 30 adjustment of the socket on the axis of the shade holder is afforded as in the construction first described.

Various other types of yoke may be utilized and modified constructions of the socket 35 to coöperate therewith will readily occur to those skilled in the art. The underlying thought of the invention is to provide a socket mount of such character that the socket may be adjusted longitudinally on the axis of the shade or its carrier so that the lamp may be brought into the focal center 40 of the shade or globe.

I claim as my invention—

1. The combination with a socket carrier, 45 of a lamp socket having longitudinally stepped seats, and means passing through the socket from its lamp-receiving end for securing said carrier and socket together on any of said seats, substantially as described.

50 2. The combination with a socket carrier, of a lamp socket having on opposite sides of its axis corresponding groups of longitudinally stepped seats adapted to receive the carrier, and means passing through the 55 socket from its lamp receiving end for securing the carrier to the socket on any of said seats.

3. The combination with a socket carrier, of a lamp socket having on opposite sides

of its axis corresponding arcuate groups of 60 longitudinally stepped seats adapted to receive the carrier, and means for securing the carrier to the socket on any of said seats.

4. The combination with a socket carrier, of a lamp socket having on opposite sides 65 of its axis corresponding coaxial arcuate groups of longitudinally stepped seats adapted to receive the carrier, and means for securing the carrier to the socket on any of said seats.

70 5. A lamp socket having at its outer end lamp receiving terminals, and at its opposite or inner end a series of stepped seats, together with means passing through the socket from its lamp receiving end and lying outside the peripheral area of the lamp receiving terminals for securing said socket to an associated carrier resting against any of said seats.

75 6. A lamp socket having at its outer end lamp receiving terminals, and at its opposite or inner end a series of stepped seats, said socket being pierced outside the peripheral area of the lamp receiving terminals in register with each of said seats to permit the 80 passage of a securing means therethrough, substantially as described.

7. A lamp socket having at its outer end lamp receiving terminals, and at its opposite or inner end a series of stepped seats, said 90 socket being pierced in register with each of said seats to permit the passage of a securing means therethrough, said piercings being shouldered at like distances from the 95 seats for the purpose described.

8. The combination with a socket carrier, of a lamp socket adjustable thereon longitudinally with respect to the axis of the socket, and having an insulating base, lamp receptacle terminals mounted thereon and 100 securing means accessible from the lamp receiving end of the socket for uniting said base and carrier in longitudinally adjusted position in different relative rotary relations of the said base and carrier.

105 9. The combination with a socket carrier having spaced supporting legs, of a socket having series of seats therefor stepped longitudinally with relation to the axis of the socket, and means extending from the lamp receiving end of the socket and engaging the ends of said supporting legs in any of the positions of adjustment between the socket and its carrier to secure the same together.

110 In testimony whereof I have signed my name to this specification.

GEORGE B. THOMAS.
